UNITED STATES PATENT OFFICE.

GEORGE J. GLOTZBACH, OF AUSTIN, ILLINOIS, ASSIGNOR TO AMERICAN CAN COMPANY,
OF NEW YORK, N. Y., A CORPORATION OF NEW JERSEY.

PROCESS OF ORNAMENTING METAL.

1,204,005.

Specification of Letters Patent.

Patented Nov. 7, 1916.

Application filed June 8, 1914. Serial No. 843,752.

To all whom it may concern:

Be it known that I, GEORGE J. GLOTZBACH, a citizen of the United States, residing in Austin, in the county of Cook and State of Illinois, have invented a new and useful Improvement in Processes of Ornamenting Metal, of which the following is a specification.

The invention relates to the ornamentation of surfaces, preferably metallic such as tin, to produce the appearance and effect of etching, and consists in the application to the said surface, so as to become in effect a permanent part of the surface, of a substance or material which is substantially transparent or capable of becoming or being made so. A suitable substance for this purpose is gum arabic, which is applied over the surface and caused to adhere thereto by a suitable adhesive, such as varnish; but it will be understood that the invention includes any equivalent of said gum arabic suitable for the purpose. The varnish is preliminarily applied to the surface in any desired ornamental or other design, and it may be so applied by a printing process. The gum arabic preferably in rather finely comminuted, powdered form is sprinkled or dusted onto such prepared surface and will adhere thereto where the surface has been previously treated with the said varnish. The materials so applied to the surface or plate are then allowed to dry or harden, after which all surplus non-adhering gum arabic is removed, allowing to remain only that which forms the design previously printed in varnish or sizing. In this incomplete state the said design has a rough, coarse, white, opaque appearance. A coat of gloss varnish covering the entire surface of the sheet of metal is then applied, which causes the said opaque appearance to disappear and renders the gum arabic more or less transparent, giving to the whole plate and the design thereon the identical appearance of a high grade etched effect. The design formed by the said gum arabic or equivalent material will appear to have been produced on the plate in intaglio, as if the surface had been etched away by an acid, and the other parts of the plate not covered by the said gum will appear to be in relief, especially if, as is preferred, the design be originally printed upon a polished or brightly lacquered metal plate.

In order to make the invention more clearly understood I have indicated in the accompanying drawing a practical manner of carrying the same into practical effect.

In said drawings—Figure 1 is a diagram showing a portion of a metal surface having a design lithographed thereon. Fig. 2 is a similar view of the same design after the completion of the same by the application of a substantially transparent gum, on certain parts of the design, and the drying and varnishing of the gum. Fig. 3 is a sectional view of a portion of the completed plate, greatly exaggerated as to the thicknesses shown.

Referring to the drawings, 1 indicates the metal plate and 2 the design lithographed thereon, the same being shown in the drawings by black lines, but it will be understood that the design can or may be shown by any desired colors applied to the plate by a lithographic process at the places to produce the effect desired.

3 indicates the spaces which are to be shown, in the finished design, as if etched into the plate, any appropriate portions of the plate being selected for this purpose, preferably in spaces between the color printing. These parts of the plate will be covered by an adhesive varnish 7 (Fig. 3) which will take and hold the comminuted gum, while the residue of the latter may be removed or dusted off from all the other parts of the plate. Ordinarily the portions selected to be shown as if etched will be parts of what may be termed the background of the design, which parts may be advantageously covered, for instance, by gold or silver lacquer. 4 (Fig. 2) indicates the same spaces 3 having applied thereto a transparent gum, which has been dried and covered with a finishing gloss varnish. The effect of this is to give to those portions of the design to which the gum has been applied a substantially transparent and slightly grained appearance, which in contrast with the normally smooth surface of the metal plate appears to be the result of etching into and below the surface of the plate, the normal surface of the plate indicated at 5 appearing to the eye to stand out above the said portions 4 which have been covered by the said gum; whereas in fact the normal surface 5 of the plate is slightly below the parts that appear to be etched into the plate, to the extent of 110

the slight thickness of the gum which has been applied. The last step is to apply the said gloss varnish 6 over the entire plate, which has the effect of causing the gum to be substantially transparent and the apparent intaglio etching to look deeper and throws the other parts of the plate more into apparent relief.

The design may be entirely of the character above described, but very beautiful effects may be produced by combining therewith designs, and lettering, of any desired character, in various artistically selected colors and tints; all of which may be applied 10 to the plate at the outset and before the first adhesive varnish is applied, by lithographic printing. The general appearance of such a colored design interspersed with the said apparently etched design, and interspersed 15 with lines where the polished or brightly lacquered parts of the metal plate appear, closely approximates that of cloisonné enamel work, and yet the ornamentation is produced simply and with comparative cheapness of material and work. For 20 example a floral design may be produced, interspersed with lettering, in various different colors; certain parts of the plate may be left with the polished tinned surface exposed, giving a silvered effect; other parts of the plate may be treated with a bright yellow lacquer, giving a golden effect; and on the plate thus prepared the etched design may be printed in adhesive varnish or 25 equivalent substance on the said silver and golden surfaces. Thereafter the gum arabic or its equivalent is applied as already described. Finally, a gloss varnish of a transparent character is applied over all, giving 30 to those parts of the plate covered by the gum arabic a substantially transparent appearance to show the metal beneath, or the underlying lacquer, and adding to the brilliancy of the whole design.

40 To give a practical example of carrying out the process: The first printing is in yellow, applied to all parts of the plate where the intended design requires that color; the second printing is in red; the third printing is in lacquer; the fourth printing is in black; the fifth printing is in light blue; the sixth printing is in dark blue; the seventh printing is of the so-called etched design, in varnish or sizing consisting of burnt linseed oil and gums; the next operation is 45 that of applying the pulverized gum arabic, which may be sprinkled or dusted on or applied with cotton or soft wool; after drying and hardening, and the removal of all 50 surplus powder, allowing only the etched appearing design to remain, the gloss varnish, mainly of resin, is applied over all to brighten and protect the whole design and to give to the gum arabic a substantially transparent and etched appearance.

The above described process is in most cases an efficient substitute for the slow and costly acid etching process.

It will be understood that the metal is first cleaned as usual for printing. The adhesive varnish by which the gum is attached is or may be colorless, and is applied at points where the plate is to appear to be etched out and it is not applied where the plate is to appear to be in relief. The best 70 result is attained by applying the gum in form of powder, not so fine as flour but having a palpable grit. The gum, after application, will dry in the atmosphere, but the process may be hastened by putting 75 the plate having the gum applied thereto through a heater of about 140° or 150° F. The final coating of thin and clear gloss varnish both enhances the effect and also acts as a preservative.

The metal thus produced may be used in the flat, as for signs, or may be cut and worked up into cans, boxes, receptacles of various kinds, and a great variety of articles, of a richly ornamented appearance.

I claim:

1. A process for the ornamentation of metal, to produce the effect of etching, which consists in applying to the metal plate in powdered condition a material capable of 95 being rendered substantially transparent and arranged according to the desired design, and applying to the plate over the said material a varnish to render the said material substantially transparent and produce 100 the effect of being etched.

2. A process for the ornamentation of metal, to produce the effect of etching, which consists in applying to the metal plate a substantially transparent gum in comminuted form and arranged according to the desired design on those parts of the plate which are to appear etched out, leaving exposed parts of the plate which are to appear 105 in relief, drying the gum, and applying over 110 the gum a gloss varnish; substantially as specified.

3. A process for the ornamentation of metal, which consists in printing the desired design upon the plate with varnish or sizing, then applying to the plate comminuted gum and causing it to adhere to the varnish or sizing, and then after the gum is dry applying over the gum a gloss varnish; substantially as specified.

4. A process for the ornamentation of metal, which consists in lithographing a design upon a metal plate, in any desired colors; then lithographing a design on the plate, with an adhesive; then applying gum 125 in comminuted form on the adhesive; and then, after the gum is dry, applying a varnish over the gum to render it substantially transparent; substantially as specified.

5. A metal plate having a design thereon 130

in the semblance of an etching, and composed of an adhesive and comminuted gum held by the adhesive, the gum being rendered substantially transparent by an externally applied varnish; substantially as specified.

6. A metal plate having a design thereon in the semblance of an etching, and composed of an adhesive and a powdered material capable of being rendered substantially

transparent and held by the adhesive, the said material being rendered substantially transparent by an externally applied varnish.

In testimony whereof I affix my signature ¹⁵ in the presence of two subscribing witnesses.
